UNITED STATES PATENT OFFICE

WILLIAM V. KNOLL, OF DAYTON, OHIO, ASSIGNOR TO THE MID-WEST MACHINE COMPANY, OF DAYTON, OHIO, A CORPORATION OF OHIO

SYSTEM OF AND APPARATUS FOR THE TREATMENT OF PAPER PULP

Application filed October 4, 1926. Serial No. 139,439.

This invention relates to paper pulp preparation and more particularly to a beater engine and a system of pulp circulation to and from the beater.

At the present time most paper stock is treated in beater engines in which the pulp moves horizontally and is operated upon by a roll or drum of comparatively large size ranging from forty-eight inches to seventy-
10 two inches in diameter. This drum or roll not only tends to disintegrate the stock but it also acts as a conveyor for moving the stock, which it elevates over a comparatively high back fall or scroll plate in order to give the
15 stock sufficient momentum to induce its return to the beater drum or roll for reworking. Such system of pulp treatment is very inefficient, and the output is small in proportion to the size and weight of the equipment
20 and the necessary power expended in its operation.

In the present invention there is contemplated a system wherein the efficiency and output will be materially increased, with
25 minimum power consumption. To this end there is employed a beater roll or drum of comparatively small size, and which is operated at high speed. This high speed, small size roll or drum is completely enclosed or
30 housed and performs only the beating or disintegrating operation and is not required to move the pulp or to serve as a conveyor or elevator. The pulp material is supplied to the enclosed or housed high speed beater
35 drum under pressure, preferably by gravity from a supply tank affording a sufficiently high head, of pulp. At the output side of the small size, high speed enclosed beater roll there is provided a rotary pump which
40 produces a vacuum or suction effect at the output side, removing the pulp as fast as it passes the high speed drum or roll, thus enabling full effect of the supply head of pulp. This rotary pump induces the circulation of
45 the pulp, either returning it to the original supply tank, for reworking, through the same beater engine, or discharging it to a succeeding supply tank of a series from which it is conducted through one or more additional beater engines.

The present system consists of a storage tank located in elevated relation, above the beater roll to afford the necessary head or gravity pressure. The beater roll is completely enclosed and performs only the disintegrating or beating operation, while the centrifugal pump, with which the outlet of the beater is connected performs the operation of circulating and elevating the pulp preparatory to reworking it, whether the reworking
60 be through the same beater engine or through a succession of supply tanks and beater engines.

The beater engine itself being of comparatively small size, and operated at a relatively
65 high speed comprises a drum mounted in fixed bearings, and having longitudinal dovetail slots in which the fly bars are secured by wedging. The bed plate cooperating with the
70 drum or roll is vertically adjustable by means of oppositely disposed relatively adjustable wedge blocks operated by a right and left hand adjusting screw.

The object of the invention is to simplify
75 the structure as well as the means and mode of operation of pulp treating systems whereby they will not only be cheapened in construction but will be more efficient in use, positive in operation, uniform in action, operated with less power, and unlikely to get out of
80 repair.

A further object of the invention is to provide an improved system for pulp circulation whereby the pulp is supplied under gravity pressure to the beater roll and is circulated by a pump operating independent of the beater roll and serving to maintain a reduced pressure at the output side of such roll to thereby render the head pressure of the plug supply
85 effective.

A further object of the invention is to provide an improved system of pulp treatment wherein the pulp may be returned to the original supply tank for reworking, or may be
90 carried through a succession of supply tanks from each of which it is fed to a beater roll to afford a continuous system of operation.

A further object of the invention is to provide an improved form of beater roll and im-

proved means for mounting the fly bars therein.

A further object of the invention is to provide improved means for adjusting the bed plate and drum of the beater engine relative to each other.

With the above primary and other incidental objects in view as will more fully appear in the specification, the invention consists of the features of construction, the parts and combinations thereof, and the mode of operation, or their equivalents, as hereinafter described and set forth in the claims.

In the drawings wherein is shown the preferred, but obviously not necessarily the only form of embodiment of the invention, Fig. 1 is a general view somewhat diagrammatic of a continuous system of pulp working apparatus embodying the present invention. Fig. 2 is a similar view of a repetition or batch operating apparatus. Fig. 3 is a side elevation, partly broken away of the beater engine. Fig. 4 is a detail transverse sectional view illustrating the adjusting means for the bed plate of the beater. Fig. 5 is a detail view illustrating the manner of securing the fly bars in the drum. Fig. 6 is a detail view of one of the fly bar wedges.

Like parts are indicated by similar characters of reference throughout the several views.

In the drawings there is shown in Fig. 1 an arrangement of tanks and beaters forming a continuous system of treatment of pulp for paper making and the like. For convenience of installation and attendance, the apparatus is installed on two floors of a mill. On the upper floor, at the left in Fig. 1 there is shown the usual shredder 1. From the shredder 1 the material passes over the conveyor 2 to a breaker beater 3, of the usual horizontal vat type. This breaker beater is shown provided with the usual large rotary roll beater 4 operating to disintegrate the stock and at the same time elevate it to induce the circular flow of stock in the tub or vat. The shredder and breaker beater perform no part of the present invention, and any other forms of apparatus may be substituted therefor, to effect the preliminary preparation of the stock.

From the breaker beater 3 the stock is discharged into the first of a series of pulp supply tanks 5. The tanks 5 are each of sufficient height to afford a considerable "head" of pulp enabling the pulp to be discharged therefrom by gravity under pressure. Each tank 5 has an outlet 6 at the bottom which is connected to the intake side of a beater engine 7.

Whereas the ordinary beater engine of the open horizontal course type employs a beater roll of large diameter, ranging from forty-eight to seventy-two inches in diameter, which not only beats or shreds the stock, but elevates it over a back fall or scroll plate to induce circulation in the tub or vat, and re-

quires approximately sixty horse power for operation, at approximately 120 R. P. M. the present beater engines are small size and high speed, operating under less power. While the size and speed of the beater 7 may vary within a considerable range, the preferable size has been found to be approximately two feet in diameter and of about three feet face, operating in excess of three hundred R. P. M. with a power requirement of less than ten horse power. The stock is supplied to such beater by gravity feed under pressure from the preceding tank 5 of the series. The small high speed roll coacts with a bed plate which has but little elevation above the lowest point of the periphery of the roll, and the roll is not required to propel or elevate the stock. Consequently it is operable with a minimum power requirement, a power consumption of ten horse power or less being amply sufficient under ordinary conditions.

The small size high speed beater roll is completely housed and the outlet from such beater housing is connected with the suction side of a power pump 8. This pump is preferably of the centrifugal type and is of such operating capacity as to maintain a comparatively low pressure of suction effect upon the output side of the beater roll, thus rendering effective the high "head" of pulp in the preceding supply tank 5, to enable a gravity forced feed. The pump 8 elevates the pulp through an uptake conduit 9 preparatory to reworking. In the present instance the system is shown as discharging the pulp from the uptake conduit 9 through an auxiliary beater 10 of similar construction. That is to say the beater 10 is also preferably of the small size and high speed type. The roll is enclosed in the housing and the pulp is supplied under pressure. In this case it is supplied by the pump 8. The discharge from the auxiliary beater 10 is by gravity through a down spout 11, which serves somewhat as a pen stock and exerts a low pressure or suction effect upon the output side of the beater 10.

In the "continuous" system illustrated in Fig. 1, the pulp after passing the intermediate beaters 8 and 10 is discharged into the succeeding tank 5 of the series and the operation is repeated any desired number of times. The result is a continuous output of finished pulp from the final stage. To meet unusual conditions or requirements for especially refined pulp, the uptake conduit 9 of the final stage, and leading from the last pump 8 of the series, may be provided with a return branch conduit 12 having therein a control valve 13 enabling the return of the pulp from the final stage of operation to the first tank 5 for reworking. The finished pulp is discharged through the valve outlet conduit 14.

In lieu of the multiple stage system shown

in Fig. 1, there is illustrated in Fig. 2 a "batch" treatment apparatus in which the stock is constantly returned to the single tank 5 for reworking, until it is reduced to the required condition. This repetitious system is in all respects similar to the multiple stage continuous system of Fig. 1, and embodies the same relation and arrangement of the small size speed beater 7 supplied with stock under gravity pressure from the supply tank 5, which head of stock is rendered effective by the low pressure output maintained by the pump 8 which elevates the stock through the uptake conduit 9 for discharge back to the tank through the auxiliary beater 10. When the pulp stock is finished it is discharged through one of the other of the valved discharge conduits 14.

The pressure fed small size high speed beater engine of preferred form is illustrated in Figs. 3 to 5. The roll 15 preferably comprises a cast metal drum, formed hollow to reduce its weight. The hollow metallic drum is provided with longitudinal slots 16 in its periphery to receive a series of fly bars 17. The slots 16 have one side inwardly divergent with a radius passing through the slot, while the opposite face of the slot is oppositely divergent causing the slot to be enlarged inwardly to afford a somewhat "dovetail" shape. The inner margins of the fly bars 17 are similarly shaped for parallel agreement with the sides of the slots, but are of less thickness than the width of the mouths of the slots thus enabling the enlarged inner margins to be easily inserted in the slots of the drum, where they are secured by driven wedges 18. The open spaces of the slots contiguous to the fly bars are then filled with Babbett metal, surrounding and embedding the driven wedges 18. To effect an interlocking engagement of the driven wedges 18, recesses or cavities 19 are formed in the sides of the slots 16 and the wedges 18 are notched or recessed to receive the flow of Babbett metal thereby interlocking the wedges with the drum.

The roll, comprising the hollow metallic drum and fly bars affixed therein is revolvably mounted in fixed bearings and coacts with an adjustable bed plate 20.

The bed plate comprises a succession of spaced plates and intermediate fillers of wood, mounted in a vertically adjustable holder or carrier 21 formed in two sections between which the plates and fillers comprising the bed plate are clamped.

The under side of the holder or carrier 21 is provided with downwardly convergent cam faces 22 formed integral therewith. In spaced relation below the inclined under surface of the bed plate carrier is a sub base member 23 having like inclined cam faces 24 on its top surface. Confined between the cam faces 22 and 25 by lateral angle plates 25 is

a pair of longitudinally adjusting wedges 26. The inclined blocks or wedges 26 serve as space blocks between the base 23 and the holder or carrier 21 for the bed plate and support the latter. A screw shaft 27 having right and left threads and journaled in the upstanding ends of the base 23 serves to adjust the inclined space blocks or wedges 26 which are screw threaded thereon. By rotating the screw shaft to adjust the blocks 26 toward each other the bed plate is elevated in relation with the roll. The bed plate holder 21 is secured in its adjusted position by set screws 28 which limit the upward adjustment and clamp the bed plate carrier against the inclined blocks or wedges 26.

The beater roll is completely enclosed by a housing 29 having an inlet 30 which communicates with the supply tank 5 to supply stock under pressure, and an outlet 31 which communicates with the suction side of the pump 7. The fact that the pulp stock is supplied under a high head or pressure at the intake side and is delivered at a much lower pressure at the output side, necessitates the housing 29 being substantially leak proof. Obviously an open type beater would be impractical under the present operating conditions.

The system is quite flexible in its operation, and readily accommodates itself to different conditions of operation and various requirements. The beaters and pumps are preferably operated by variable speed motors enabling the rapidity of circulation of the pulp to be varied and by varying the pump capacity and thereby the output pressure or suction effect upon the roll, the effective "head" or feeding pressure is also varied. That is to say any back pressure of stock from the uptake conduit will tend to equalize or balance to greater or less extent the head pressure of stock at the intake side of the beater. Thus not only is great flexibility afforded but the operator is given minute control over the function and operation of the apparatus.

From the above description it will be apparent that there is thus provided a construction of the character described possessing the particular features of advantage before enumerated as desirable but which obviously is susceptible of modification, in its form, proportions, and arrangement of parts, without departing from the principle involved or sacrificing any of its advantages.

While in order to comply with the statute the invention is described in language more or less specific as to structural features, it is to be understood that the invention is not limited to the specific details shown, but that the means and construction herein disclosed comprise the preferred form of several modes of putting the invention into effect, and the invention is therefore claimed in any of its

forms or modifications within the legitimate and valid scope of the appended claims.

Having thus described my invention, I claim:—

- 5 1. In a construction of the character described, a revoluble beater roll, a pressure housing completely enclosing the roll and having inlet and outlet openings, means for supplying pulp thereto under pressure, fixed 10 journal bearings for the roll, and adjustable bed plate, and means for adjusting the bed plate relative to said roll.
- 15 2. In a beater engine for paper pulp and the like, a beater roll of less than thirty inches diameter and operable at a rate of more than three hundred R. P. M., a housing therefor, a bed plate adjustable in relation with the roll and means for supplying pulp thereto under pressure.
- 20 3. In a beater engine for paper pulp and the like, a beater roll, comprising a drum having longitudinal spaced slots in the periphery thereof, said slots having inwardly divergent walls, fly bars located in the slots, said fly bars being flared on their inner margins to agree with the taper of the slots, and wedges inserted in the slots beside the fly bars for maintaining the fly bars in place said slots having recesses formed in their inner faces 25 and the wedges also being recessed and a body of sealing material molded in situ in said slots and extending into the recesses of the slots and wedges.

In testimony whereof, I have hereunto set my hand this 27th day of September, 1926.

WILLIAM V. KNOLL.
